E. R. ADDISON, OF WHEELING, WEST VIRGINIA.

Letters Patent No. 70,935, dated November 19, 1867.

IMPROVEMENT IN LAMP-CHIMNEYS.

The Schedule referred to in these Letters Patent and making part of the same.

TO ALL WHOM IT MAY CONCERN:

Be it known that I, E. R. ADDISON, of Wheeling, in the county of Ohio, State of West Virginia, have invented a new and useful Improvement in Lamp-Chimneys; and I do hereby declare the following to be a full, clear, and exact description of the nature, construction, and operation of the same, sufficient to enable one skilled in the art to which it appertains to construct and use the same, reference being had to the accompanying drawings, which are made part of this specification, and in which the same letters indicate similar parts, and the invention is represented by a vertical central section.

Supported above the flame, and upon the upper edge of the bulb, is a chimney, of metal or mica.

In the drawings, A is the glass bulb, inside which the red lines represent the wick B and the flame c. Above the latter is a conical or trumpet-shaped tube, D, supported by a dome, E. The tube D and dome E may be made of metal, mica, or other incombustible material, the lower margin of the dome fitting by a flange upon the rim of the bulb A, and the lower edge of the tube D extending down to a point as near the flame as may be desirable.

To make the chimney operate in the best manner, it should be secured, as shown, by a single circular line of attachment to the dome at a, by which only the heat in the chimney will be conducted to the dome E, and the air rising against the bulb will revert in the mode indicated by the arrows, and tend to carry the heated air continually towards the point of exit, (the tube D,) and abate the heat of the tube.

By this device the bulb is less heated than when the chimney consists of one piece of glass, as the heat is principally concentrated on the tube, and, so far as conduction is concerned, can only pass to the bulb through the point of junction with the dome, and through the latter to the top rim of the tube. By this arrangement there is much less aberration of the flame in moving about than in ordinary chimneys, and consequently less smoke, and what may be deposited will be principally on the tube D. The tube D may be made to slide up or down, to increase or diminish the draught, or it can be made stationary in the supporting-dome E.

In William Starkey's lamp-chimney, patented March 1, 1864, a space is left between the upper end of the dome and the inner chimney. The heated gases are thus caused to pass, not only within the metal chimney, but around it in contact with the glass, thus heating and endangering breakage of the latter. By connecting the dome by joints, at both a and e, sufficiently tight to prevent any free passage of air, I avoid the difficulty above named.

Having described my invention, what I claim as new, and desire to secure by Letters Patent, is—

The combination with the glass bulb A of the metallic or mica chimney D, secured by tight joints a and e to the upper edge of the bulb, substantially as described and represented.

E. R. ADDISON.
